(57) **CLAIM**

I claim the ornamental design for a trocar, as shown and described.

DESCRIPTION

FIG. 1 is a perspective view of a trocar showing my new design;

FIG. 2 is a front elevational view of the trocar of FIG. 1;

FIG. 3 is a rear elevational view of the trocar of FIG. 1;

FIG. 4 is a left elevational of the trocar of FIG. 1;

FIG. 5 is a right elevational view of the trocar of FIG. 1;

FIG. 6 is a top plan view of the trocar of FIG. 1; and,

FIG. 7 is a bottom plan view of the trocar of FIG. 1.

The broken lines are provided for the purpose of illustrating portions of the trocar and form no part of the claimed design.
